LAMP SOCKET

De Soto E. Richardson, Azwell, Wash.

Application November 3, 1939, Serial No. 302,731

3 Claims. (Cl. 173—358)

This invention relates to improvements in lamp sockets and more particularly to a spring socket for attachment to the conventional screw socket.

It is an object of the invention to provide a spring socket for lamp bulbs which will permit the ready changing of the lamp bulbs without the necessity of unscrewing the bulb and consequently with less danger of breakage.

A further object of the invention resides in providing a spring socket attachment having spring arms for establishing a firm and positive connection between the attachment and conventional socket to prevent accidental detachment of the attachment.

Another object of the invention resides in providing a device of the above-mentioned character which is simple and durable in construction, reliable and efficient in use, and inexpensive to manufacture.

Other objects and advantages of the invention will be apparent during the course of the following description.

In the accompanying drawing forming a part of this specification and in which like numerals are employed to designate like parts throughout the same,

Fig. 1 is a sectional view of the spring socket applied to a conventional lamp socket,

Fig. 2 is a top view of the spring socket,

Fig. 3 is a side elevation of the spring socket, partly in vertical section,

Fig. 4 is a perspective view of the spring socket with the shell removed, and

Fig. 5 is a vertical section of the shell.

In the drawing, wherein for the purpose of illustration I have shown a preferred embodiment of my invention, the numeral 5 indicates a conventional lamp socket having the usual screw threads 6 to receive the threaded base 7 of an ordinary electric light bulb 8.

Referring to my attachment, a metal disk 9 has bent from its peripheral edge a series of upwardly extending spring arms 10 which are spaced equidistantly, the upper ends of the arms being bent inwardly and recessed, as at 11, to snugly engage the outer wall of a tube 12, near its upper end. The intermediate portion of the arms 10 have spaced projections 13 struck therefrom which are adapted to threadedly engage the screw threads of the socket 5 and are forced into tight engagement therewith by the spring pressure of the arms 10 which normally presses the arms outwardly. The tube 12 is disposed centrally of the disk 9 and is attached thereto

by lugs 14 which extend through openings in the disk, the lugs being turned over to securely fasten the tube and disk together. A contact member 15 is slidably fitted within the tube 12 and through this contact member extends a wire 16. The member 15 is formed of insulating material and has a reduced lower portion 17 about which fits a coil spring 18 having one end bearing against a shoulder 19 and its other end on the disk 9. The spring normally urges the contact member 15 upwardly but when the attachment is fitted in the socket 5, the contact member is depressed, thus forcing its lower end to project through the central opening 20 in the disk 9, so that it will contact with the base of the light bulb 8 when fitted into the socket of the attachment.

The socket of the attachment consists of a tubular sleeve 21 formed of Bakelite or other 20 suitable material which is attached to the disk 9 by downwardly turned spring fingers 22 which are bent from the disk intermediate the spring arms 10 and project into engagement with the inner wall of the sleeve 21, the terminals of the 25 fingers being bent outwardly to engage in recesses 23 formed in the walls of the sleeve. A series of downwardly extending spring arms 24 are arranged alongside of the spring fingers and extend the full length of the sleeve 21 with 30 their intermediate portions bowed outwardly from the inner wall of the sleeve to form projections 25 adapted to resiliently engage with the threads of the lamp base 7 when the same is inserted in the socket, thereby detachably 35 securing the lamp bulb in the socket.

In use, the spring socket attachment may be applied to a conventional screw lamp socket, by screwing the spring arms 10 into the socket until the contact member 15 engages with the 40 contact in the bottom of the socket. Owing to the normal outward pressure of the spring arms, a tight fit is established between the arms and socket, firmly securing the attachment to the socket. The lamp bulb 8 is secured in the socket of the 45 attachment by inserting the base 7 in the sleeve 21 and is held therein by the spring arms 24 which resiliently grip the threads of the base. Owing to the resiliency of the arms 24 the lamp 50 may be readily inserted or removed from the socket of the attachment by forcibly inserting or removing the lamp bulb.

It is to be understood that the form of my invention herein shown and described is to be taken as a preferred example of the same and that certain changes in the shape, size, and arrange-

ment of the parts may be made without departing from the spirit of the invention or the scope of the subjoined claims.

Having thus described my invention, I claim:

1. A spring socket attachment comprising a metal disk, a tube extending upwardly from the center of said disk, a contact member mounted in said tube and slideable longitudinally therethrough, a spring urging the contact upwardly, spring arms extending upwardly from the periphery of said disk and having their upper ends bent inwardly into engagement with the outer wall of said tube and their intermediate portions crimped for engagement with the threaded shell of a lamp socket, spring fingers extending downwardly from said disk between said arms, a tubular sleeve suspended from said spring fingers, and spring arms extending downwardly from said disk for substantially the length of said sleeve and having portions intermediate their ends crimped to form teeth for gripping the base of a light bulb.

2. A spring socket attachment comprising a metal disk, a sleeve extending downwardly from said disk, spring strips extending radially from the disk and bent downwardly from said disk and slit to form arms and fingers, the arms extending the length of said sleeve and crimped to form

teeth for gripping the threaded base of a light bulb and the fingers having their lower ends bent to form hooks for engaging in recesses formed in the sleeve and supporting the sleeve, a contact member extending upwardly from the center of said disk, and spring arms extending upwardly from the periphery of said disk between said strips and having their intermediate portions formed with projections for engagement with the screw threads of a conventional lamp socket.

3. A spring socket attachment comprising a metal disk, a sleeve extending downwardly from said disk, spring arms bent downwardly from said disk and extending the length of said sleeve and having intermediate portions bent to form teeth for gripping the threaded base of a light bulb, a tube extending upwardly from said disk, a contact member slidably mounted in said tube with its lower end passing through the disk into the sleeve, a spring normally urging said contact member upwardly, and spring arms bent upwardly from said disk and having their upper ends bent inwardly into engagement with said tube whereby said spring arms are normally forced outwardly and their intermediate portions crimped to form threads for meshing with the threaded shell of a light socket.

DE SOTO E. RICHARDSON.
